CLAIM

The ornamental design for a combined transceiver and mounting bracket for use in intercom devices, as shown and described.

DESCRIPTION

FIG. 1 is a front perspective view of the transceiver mounting bracket, shown separately for illustrative purposes only;

FIG. 2 is a perspective view of the combined transceiver and mounting bracket therefor;

FIG. 3 is a side elevation thereof;

FIG. 4 is a side elevation of the mounting bracket;

FIG. 5 is a rear elevation of the transceiver;

FIG. 6 is a front elevation of the transceiver;

FIG. 7 is a top plan view thereof; and

FIG. 8 is a bottom plan view thereof.

FIG. 1

FIG. 2

FIG. 3

FIG. 4

FIG. 5

FIG. 6
